UNITED STATES PATENT OFFICE

STANLEY C. NORTH, OF SYRACUSE, NEW YORK

WRENCH

Application filed April 26, 1927. Serial No. 186,669.

This invention relates to a new and improved adjustable wrench.

The main object of my invention is to provide a wrench in which the distance between the jaw members can be varied in an easy and rapid manner, and the jaw members locked in spaced relation by a simple and convenient device.

Other objects and advantages relate to the details and form of the device as will more fully appear from the following description taken in connection with the accompanying drawings, in which:

Figure 1 is a perspective view of the wrench.

Figure 2 is a section, partially in elevation, taken on line 2-2, Figure 1, with part of the handle broken away.

Figure 3 is a section on line 3-3, Figure 2. In the drawings like numbers refer to like parts, and the description will refer to the parts as shown in the drawings.

The body 1 of the wrench is formed at one end into a handle 2 and carries at the other end a jaw 3 extending downwardly from and at substantially a right angle to the body 1. The jaw 3 has a flat face 4 on the side facing the body 1 which is adapted to engage a nut (not shown). The edge of the body 1 which is opposite the face 4 carries a series of ratchet teeth 5, 5 beginning approximately at the face 4 and extending rearwardly to the handle 2.

A complementary jaw member 6 is formed with a body portion 7 and a jaw 8 extending downwardly from and substantially at a right angle to the body portion 7. The outside face 9 of the jaw 6 is flat and of substantially the same size and shape as face 4.

The upper side of jaw member 6 is cut away at each end to form shelves 10 and 11, which shelves are provided with bottomed holes 12 and 13 adapted to receive springs 14 and 15 underneath balls 16 and 17. Between shelves 10 and 11 and in a plane higher than shelves 10 and 11 is a series of ratchet teeth 18-18 of a size and shape

to mesh with ratchet teeth 5, 5. The body portion 7 carries, in spaced relation, fixed pins 19 and 20 which extend outwardly from both sides of jaw member 6. A fixed pin 21 extends downwardly from the bottom of jaw member 6 and is positioned approximately half way from front to back.

A saddle member 22, having slotted holes 23, 23 in both sides, is slidably mounted on body portion 1 and extends downwardly therefrom. Jaw member 6 is mounted in saddle 22 by means of pins 19 and 20 which extend outwardly thru slots 23, 23. Said jaw member 6 is assembled with ratchet teeth 18, 18 in juxtaposition to ratchet teeth 5, 5. A lever 24 having a cam-shaped end 25 is pivotally mounted in saddle 22 by means of pivot pin 26 positioned below jaw member 6 and so disposed that in one position of the lever 24 the cam end 25 will engage the bottom of jaw member 6 and force it upward until the cam end 25 is stopped by pin 21. In another position of lever 24, as perhaps may best be seen by dotted lines in Figure 2, the cam member 25 is retracted from jaw member 6 until its downward movement is stopped by fixed pin 27 positioned in saddle 22.

The method of use of my wrench is as follows:

The lever 24 is moved downwardly, thus removing pressure on jaw member 6 and permitting the springs 14 and 15 to force the balls 16 and 17 against the ratchet teeth 5, 5 and hold the ratchet teeth 18, 18 out of engagement with ratchet teeth 5, 5, the slotted holes 23-23 permitting this movement of supporting pins 19 and 20.

With the jaw member 6 in this position the saddle 22 can easily be pushed back and forth along body 1 until the faces 4 and 9 are positioned in the desired spaced relation for use with a given nut. When the faces 4 and 9 are in the desired position, lever 24 is raised upwardly causing the ratchet teeth 18-18 to mesh with ratchet teeth 5, 5.

—18, 18— to mesh with ratchet teeth —5, 5— and lock jaw member —6— to body —1—.

Although I have shown and described a specific construction and form of parts as 5 illustrative of an embodiment of my invention I do not desire to restrict myself to the exact form, shape or arrangement of the parts as various changes may be made within the scope of the appended claims.

10 I claim:

1. In a device of the class described, a wrench body having a series of ratchet teeth on one edge thereof and carrying a fixed jaw member, a saddle slidably mounted on 15 the wrench body, a second jaw member having a series of ratchet teeth on one edge thereof slidably mounted in the saddle for movement relatively thereto, a pair of spaced apertures in the second jaw member, 20 a ball movably mounted in each of the apertures, a spring in each of the apertures exerting pressure against the ball in the apertures to press the balls against the ratchet teeth of the wrench body to normally 25 hold the wrench body and the slidable jaw member in spaced relation, and a lever pivotally mounted in the saddle for moving a cam in contact with the slidable jaw member whereby the ratchet teeth on the slidable 30 jaw member will be held in mesh with the ratchet teeth on the wrench body.

2. In a device of the class described, a wrench body having a series of ratchet teeth on one edge thereof and carrying a fixed 35 jaw member, a saddle slidably mounted on the wrench body, a second jaw member having a series of ratchet teeth on one edge thereof slidably mounted in the saddle for movement relatively thereto, a pair of spaced 40 apertures in the second jaw member, a ball movably mounted in each of the apertures, a spring in each of the apertures exerting pressure against the ball in the apertures to press the balls against the ratchet teeth 45 of the wrench body to normally hold the wrench body and the slidable jaw member in spaced relation, and a lever pivotally mounted in the saddle for moving a cam in contact with the slidable jaw member whereby the ratchet teeth on the slidable jaw member will be held in mesh with the ratchet teeth on the wrench body, the point of contact between the cam and the slidable jaw member being between the apertures.

55 In witness whereof I have hereunto set my hand this 16th day of April, 1927.

STANLEY C. NORTH.
